(57) CLAIM

The ornamental design for a shirt and underwear combination, as shown and described.

DESCRIPTION

FIG. 1 is a front perspective view of a shirt and underwear combination with the bottom portion of the shirt upwards showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view of a shirt and underwear combination of FIGS. 1-7 shown with the bottom portion of the shirt down;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The even-length broken lines represent stitching that forms no part of the claimed design.
